UNITED STATES PATENT OFFICE.

HARRY W. FAHNESTOCK, OF CHICAGO, ILLINOIS.

SIGNAL-FLAG HOLDER.

Application filed May 27, 1927. Serial No. 194,728.

My invention relates to a railway signal device for being attached to a railway rail and there locked in position so that such signal cannot be removed by someone not 5 authorized to do so.

Another and further object of my invention is the provision of a signal flag adapted for use particularly by repairmen working on tracks or railway cars which have been 10 set out on the tracks, and in which the usual custom is to protect such cars by the use of a blue flag attached to a pointed stick which is set in the ground between the rails or by attaching to the rail a flag having a spring 15 clip.

In practice a flag which is set in the ground between the rails may be blown over by the wind or it may be removed by some person not having authority to do so, with 20 the result that a car may be run into the workmen resulting in loss of life or serious injury to the workmen.

In my improved construction I provide a resiliently mounted signal flag which is 25 locked to the rail head and cannot be removed therefrom except by some authorized person who carries a key to unfasten the lock.

Another and further object of my invention is the provision of a signal flag which is resiliently mounted onto the rail and which is adapted to be secured to the rail head and project upwardly at an angle therefrom so that the signalling member is positioned 35 midway between the rails comprising a track, and in full and easy view of a trainman or engine crew in switching operations.

Another and further object of my invention is the provision of a device which is 40 simple in operation, which is efficient and easily attached to the rail head, and is easily removed therefrom, and which is adapted to fit upon rail heads of different sizes and be firmly clamped into position upon the said 45 rails.

These and other objects of my invention will be more fully and better understood by reference to the accompanying sheet of drawings and in which:—

50 Figure 1 is an elevational view of my improved invention attached to the rail head;

Figure 2 is a detailed view showing the locking members secured to a rail section; and

55 Figure 3 is a side elevational view of the device shown in Figure 2.

Referring now specifically to the drawings, a signalling member 10 is provided having a hole 11 therein near the lower side thereof within which a lantern can be hung 60 or other signalling member attached, the said signalling member 10 having a standard 12 secured thereto in any suitable manner. The member 12 is preferably made of an angle iron and at the lower end thereof has a member 13 secured thereto by means of a pair of rivets 14, 14, the said member 13 extending downward beyond the end of the member 12 and forming a projecting portion 15 which extends underneath the rail head 16 70 and upward along the inner side of the said rail head and partially over the top thereof, where its free end 17 is sloped materially to provide a bearing surface for a cooperating locking member 18. The locking member 75 18 extends parallel with the member 13 and is greater in length than the said member 13 and is secured upon a stud 19 mounted in the standard 12, the said stud 19 projecting upward from the standard 12 a sufficient distance to allow the member 18 to be lifted upward and outward so that its free end becomes disengaged from under the rail head 16. The member 18 engages an enlarged 80 portion of the stud 19 at its upper end when in locked position. The lower end of the member 18 passes over the end 17 of the member 15 and over the top of the rail head 16, and conforms to the contour of the rail head, passing therearound and has an inwardly turned end 20 adapted to engage on the under side of the rail head 16.

A member 21 is provided having a head portion 22 with an opening 23 therein through which the bow of a padlock is 95 adapted to be passed, the member 18 having an elongated opening 24 therein through which the head 22 of the member 21 is adapted to be passed, after which the bow of the padlock is inserted through the opening 23 and the device locked in position upon the rail head 16.

The operation of the device is exceedingly simple in that when it is desired to attach the device to a rail head, the padlock 105 is removed from the opening 23, the member 18 lifted out and over the end of the member 21, the stud 19 being sufficiently long to permit the member 18 to be lifted above the outer end of the member 21 and the standard is applied to the inner side of the rail head with the portion 15 projecting 110

underneath the rail head and thereafter the member 18 is secured in position across the free end 17 of the member 13, and is thereupon pressed down against the member 13 5 and the bow of the padlock inserted through the opening 23 and the device locked in position.

The members 18 and 19 are preferably made of spring steel so that they flexibly 10 hold the signal in position and also enable the device to be attached to the larger sized rail heads. For instance, if the device as illustrated is secured to a 90 pound rail, it can also be used with an 80 pound rail and 15 also a 100 pound rail. The inner edge of the member 15 being angular is adapted to engage on the under side of rail heads of different thickness and the member 18 being made of spring steel will also clamp the 20 member 15 onto the rail head even though this rail head be somewhat narrower and somewhat less in thickness than a rail head having a contour conforming exactly to the 25 inner outline of these two members. Likewise, the device can be attached to a rail head somewhat larger in size because of the 30 spring character of the metal without causing a set in the metal rendering it useless for use upon rails of lesser sizes. The minimum 35 variation in the width and depth of rail heads within the limits described, amounts to approximately 6/32 of an inch, so that in view of the spring character and the shape of the inner member of the rail, the device is readily adaptable for use within these limits.

In the removal of the flag from the rail, the padlock is unlocked and removed from the member 22, whereupon the member 18 is 40 lifted outwardly, thus loosening the member from the rail head and allowing the device to be removed from the rail head. It will be noted that the contour of the member 18 between the points of its engagement 45 with the members 13 and 17, conforms substantially to the angle of the under side of the rail head which is engaged by the end 20 of the member 18, so that when the member 18 is pushed outward in a direction corresponding to this angle, it may be easily removed from the rail head.

While I have described more or less precisely the details of construction, I do not wish to be understood as limiting myself

thereto, as I contemplate changes in form 55 and the proportion of parts and the substitution of equivalents as circumstances may suggest or render expedient without departing from the spirit or scope of my invention.

I claim:

1. A railway signal comprising in combination, a standard, a signal member secured to said standard, a rail engaging member secured to the lower end of said standard, said rail engaging member extending under the rail head at one side thereof and partially across the top of the rail head, and a second rail engaging member extending parallel with and overlapping the free end of the first mentioned rail engaging member, fastening means for securing the said second rail engaging member to the standard, and a lock receiving member secured to said standard and extending through an opening in said second mentioned rail engaging member intermediate the ends thereof.

2. A railway signal comprising in combination, a standard, a signal member secured to one end of said standard, a rail engaging member secured to the opposite end of the said standard, the said rail engaging member extending under the rail head at one side thereof and upwardly along the side of said rail head and partially thereacross on the upper side thereof, and a second rail engaging member extending parallel with said first mentioned rail engaging member, the said second member extending across the free end of said first mentioned member and into engagement with the under side of the rail head at the opposite side from the said first mentioned member, a loose connection for said last mentioned rail engaging member, and a lock receiving member extending through said last mentioned rail engaging member and the lock receiving member carried by said standard and extending through the said last mentioned rail receiving member intermediate the ends thereof whereby the said last mentioned member is secured in fixed relation to the rail head and over the free end of the first mentioned rail engaging member.

Signed at Chicago, Illinois, this 20th day 105 of May, 1927.

HARRY W. FAHNESTOCK.
